CLAIM

The ornamental design for an animated image for a portion of a display screen, as shown and described.

DESCRIPTION

FIG. 1 is a first image in the sequence for an animated image for a portion of a display screen showing our new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the ninth image thereof;

FIG. 10 is the tenth image thereof;

FIG. 11 is the eleventh image thereof;

FIG. 12 is the twelfth image thereof;

FIG. 13 is the thirteenth image thereof;

FIG. 14 is the fourteenth image thereof;

FIG. 15 is the fifteenth image thereof;

FIG. 16 is the sixteenth image thereof;

FIG. 17 is the seventeenth image thereof;

FIG. 18 is the eighteenth image thereof;

FIG. 19 is the nineteenth image thereof;

FIG. 20 is the twentieth image thereof; and,

FIG. 21 is the twenty-first image thereof

The appearance of the animated image sequentially transitions between the images shown in FIGS. 1-21. The process or period in which one image transitions to another forms no part of the claimed design. The uneven length broken line showing of the display screen is for environmental purposes only and forms no part of the claimed design. The even length broken line showing of the shapes in FIGS. 18-21 is for environmental purposes only and forms no part of the disclaimed design.
